POTENTIOMETER OR SIMILAR ARTICLE

Russell D. Ricketts and Charles J. Roach,
Los Angeles, Calif.

Application October 25, 1954, Serial No. 32,819

Term of patent 14 years

(Cl. D26—1)

FIG. 1

FIG. 2

FIG. 3

To all whom it may concern:

Be it known that we, Russell D. Ricketts and Charles J. Roach, both citizens of the United States of America and residing at Los Angeles, county of Los Angeles, State of California, have invented a new, original, and ornamental Design for a Potentiometer or Similar Article, of which the following is a specification, reference being had to the accompanying drawing, forming a part hereof.

Fig. 1 is a side elevational view of a potentiometer or similar article, showing our new design.

Fig. 2 is a similar view of the article when rotated through an arc of 90 degrees about its longitudinal axis relative to the position thereof shown in Figure 1.

Fig. 3 is an end view thereof.

We claim:

The ornamental design for a potentiometer or similar article, as shown.
